UNITED STATES PATENT OFFICE.

EDWARD S. PETRICK AND FRANK J. PETRICK, OF CHICAGO, ILLINOIS.

BOOKHOLDER.

Application filed May 20, 1926. Serial No. 110,505.

This invention relates to bookholders and its object is to provide a strong and substantial device of simple construction which can be easily operated for holding a large heavy book in open or closed position and capable of being adjusted to suit the requirements of the user.

The invention also has for its object to simplify the construction and arrangement of parts of a bookholder to enable it to be easily made and assembled, and to improve the construction and arrangement so that the bookholder will prove more efficient and stand the service and withstand the abuse to which such bookholders are ordinarily subjected.

In the accompanying drawings illustrating a selected embodiment of the invention,

Fig. 1 is a side elevation showing the holder closed.

Fig. 2 is a detail enlarged sectional view showing the holder closed in full lines and open in broken lines.

Fig. 3 is a detail enlarged sectional view showing the tilting head adjustment.

Fig. 4 is a top plan view of the holder in closed position, without the stand or support.

Fig. 5 is a section on the line 5—5 of Fig. 1.

Fig. 6 is a section on the line 6—6 of Fig. 1.

Referring to the drawings the bookholder comprises a head adapted to receive and hold the book and adjustably mounted on a standard which forms part of a stand or support. The standard 7 is mounted on folding legs 8 and a shelf 9 is secured in adjusted position on the standard above the legs by a thumb screw 10.

A segment 11 is pivoted on a pin 12 in a forked guide member 13 mounted on the upper end of the standard 7 and this segment is provided with teeth 14 which are engaged by a thumb screw 15 operating through the guide member to secure the segment and the bookholder mounted thereon in adjusted position with relation to the standard. The segment is carried by or formed integrally with a bracket 16 which has two sides 17 arranged in parallel relation. Two guide rods 18 are mounted in parallel horizontal position in the sides 17 of the bracket 16 and between these two guide rods a screw rod 19 is mounted, said screw rod having a reverse thread on its

end portions and provided at one end with a palm head 20. Mounted on the guide and screw rods, at either side of the standard, is a support 21 which has a flange 22 provided with openings to receive the three rods, the center opening receiving the screw rod being threaded to engage the thread of the rod. The support is also provided with two projections 23 spaced from the flange 22, and provided with openings to receive the two guide rods, there being no such projection for the screw rod. The guide rods and the screw rod are mounted in parallel relation in the spaced sides 17, 70 17 of the bracket 16, whereby they are held in horizontal position and in proper relation to each other. The supports are engaged with the two guide rods and the screw rod at the flanges 22 and with the guide rods at the projections 23 which are spaced from the flanges 22, whereby the supports are held rigidly in adjusted position on said rods. The leaves 24 of the bookholder are riveted or otherwise secured 80 to straps 25 which are slotted to receive the arms 21' on the supports and bent to form eyes 25' to engage the pivot pins 26, whereby the leaves are pivotally mounted on the supports. Springs 27 are fastened to the supports 21 and to cross bars 28 which are engaged with lugs 29 struck up from the straps 25. The pivot or hinge end portions 25" of the straps 25 are bent substantially at right angles to the leaves 24 so that the leaves will be spaced in closed position away from the supports 21' and in substantially parallel relation thereto. The inward closing movement of the leaves is limited by stops 30 on the arms 21. The integral pivot 95 or hinge portions engage stops 30' at the upper ends of the supports 21' to limit the opening movement of the leaves and to hold the leaves in horizontal position as indicated in broken lines in Fig. 2. The springs 27 100 are fastened to the leaves above the pivots 26 so that the upper ends of the springs will travel across the center of the pivots when the leaves are swung between open and closed positions and will hold the leaves in 105 closed position or in open position under tension.

The upper margins 31 and the top margins 32 of the leaves are bent over and crimped snugly against the inner side of 110 the leaves; the back margins 33 of the leaves are bent over and crimped snugly against

the outer side of the leaves, and these crimped portions are bent outwardly, as shown in Fig. 2, to prevent injury to the back of the book. The leaves are bent inwardly at 34 to form bottom rests for the book and the margins 35 of these bottom rests are bent over and crimped snugly against the outer side of the bottom rests. The crimped margins strengthen the leaves, 10 avoid rough sharp edges and prevent wear on the book. For this purpose I also desire to flare the upper outer ends of the leaves outwardly at 24'.

The back support 36 is provided with a 15 looped strap 37 which engages the three rods between the sides 17 of the bracket 16 whereby the back is held always in rigid position centrally disposed between the leaves to receive and support the back of the book.

20 Our invention provides a bookholder of simple construction comprising few parts which are strong and substantial, which can be easily adjusted for books of different sizes and which can be easily manipulated to open 25 or close the book. The bookholder will support the book in closed or in open position and the parts are so disposed and arranged that they are not likely to become loosened or dislodged from their proper relation during 30 ordinary usage of the bookholder.

The segment 11 is provided with a back stop 11' to engage the guide member 13 and limit the swinging movement of the head in a rearward direction. This guide member is 35 engaged with the standard 7 by means of a set screw 13' which engages an annular groove 7' in the standard to permit the head to revolve freely on the standard while it is permanently secured thereto. The rear ends 40 of the bottom rests 34 are bent downwardly at 34' so that they will clear the back edge of the bookbinding and avoid damaging it.

We are aware that changes in the form, 45 construction and arrangement of parts may be made without departing from the spirit or sacrificing the advantages of the invention and we reserve the right to make all such changes as fall within the scope of the following claims.

50 We claim:

1. In a book holder, a stand, a segment pivotally mounted in said stand, flanges formed on said segment and having an opening therein, a pair of rods rigidly supported 55 in said flanges and extending therethrough, a pair of supports slidably mounted on said rods, and means cooperating with said supports to move said supports simultaneously and equally towards or away from each other.

60 2. In a book holder, a stand, a segment pivotally mounted in said stand, flanges formed on said segment and having an opening therein, a pair of rods rigidly supported

in said flanges and extending therethrough, 65 a rod having right and left hand threads extending through said opening, a pair of supports slidably mounted on said rods and having threaded an opening therein to receive said threaded rod whereby movement 70 of the threaded rod causes both of the supports to move equally and simultaneously towards or away from each other simultaneously.

3. In a book holder, a stand, a segment 75 pivotally mounted in said stand, parallel rods rigidly mounted in said segment, a pair of supports slidably mounted on said rods and having a threaded hole therein, and a threaded rod loosely mounted in said segment and cooperating with the threaded hole in said supports whereby rotation of the threaded rod will cause said supports to move toward or away from each other.

4. In a book holder, an adjustable stand, 80 a segment pivotally mounted in said stand, flanges formed on said segment and having an opening therein, a pair of rods rigidly supported in said flanges and extending 85 therethrough, a pair of supports slidably mounted on said rods, leaves pivotally mounted on said supports, and means cooperating with said supports to move said leaves simultaneously and equally towards 90 or away from each other.

5. In a book holder, a collapsible stand, a segment pivotally mounted in said stand, flanges formed on said segment and having an opening therein, a pair of rods rigidly supported 100 in said flanges and extending therethrough, a pair of supports slidably mounted on said rods, leaves pivotally mounted on said supports, a spring for holding said leaves in open or closed position, means cooperating with said supports to 105 move said leaves simultaneously and equally towards or away from each other, and means for adjusting said stand.

6. In a book holder, a collapsible stand, a segment pivotally mounted in said stand, flanges formed on said segment and having an opening therein, a pair of parallel rods rigidly supported in said flanges and extending 110 therethrough, a pair of supports slidably mounted on said rods, leaves pivotally 115 mounted on said supports, said leaves having the inner ends thereof bent outward to keep the same from marring or tearing a book, a lug formed on each support, a removable rod mounted on the back of said leaves, a spring 120 connected to said lug and said rod for holding said leaves in open or closed position, means cooperating with said supports to move said leaves simultaneously and equally 125 towards or away from each other, and means for adjusting said stand.
